UNITED STATES PATENT OFFICE

151,022

DESIGN FOR A BASEBOARD RADIATOR
SHIELD UNIT

Henry J. Weber, Franklinville, and Donald F. Bennett, Haddonfield, N. J., assignors to Warren Webster & Company, Camden, N. J., a corporation of New Jersey

Application July 26, 1946, Serial No. 132,009

Term of patent 7 years

(Cl. D81—21)

To all whom it may concern:

Be it known that we, Henry J. Weber and Donald F. Bennett, citizens of the United States, residing respectively at Franklinville, county of Gloucester, and State of New Jersey, and Haddonfield, county of Camden, and State of New Jersey, have invented a new, original, and ornamental Design for a Baseboard Radiator Shield Unit, of which the following is a specification, reference being had to the accompanying drawing, forming part thereof.

The figure is a perspective view of a baseboard radiator shield unit showing our new design. The broken lines are for illustrative purposes.

We claim:

The ornamental design for a baseboard radiator shield unit, substantially as shown.

HENRY J. WEBER.
DONALD F. BENNETT.
